Ralph E. Moyer

By Watson E. Coleman
Attorney

UNITED STATES PATENT OFFICE.

RALPH E. MOYER, OF LUDINGTON, MICHIGAN.

WRENCH.

Application filed December 12, 1921. Serial No. 521,797.

To all whom it may concern:

Be it known that I, RALPH E. MOYER, a citizen of the United States, residing at Ludington, in the county of Mason and State 5 of Michigan, have invented certain new and useful Improvements in Wrenches, of which the following is a specification, reference being had to the accompanying drawings.

This invention relates to wrenches, and 10 more particularly to ratchet wrenches.

An object of the invention is to provide a wrench of this character including a socket member which is detachably mounted in a handle, means being carried by the 15 handle for controlling movement of the handle relative to the socket member and means carried by the handle for holding said controlling means in operative or inoperative position.

It is also an object of the invention to 20 provide a wrench of this character including a stepped handle, having a bearing member on one end adapted to receive a detachable socket member, the socket member being provided with teeth for engagement 25 with pawls carried by the bearing member, and means carried by the bearing member to permit rotary movement of the bearing member relative to the handle, and 30 prevent disengagement of the socket member from the bearing member.

It is a further object of the invention to 35 provide a wrench of this character wherein the pawls used to control the movement of the socket member are provided with cam extensions adapted to be engaged by a spring-pressed plate carried by the bearing member to hold the pawls in their operative or inoperative positions.

With these and other objects in view, the 40 invention consists in the improved construction and arrangement of parts to be herein-after more particularly described, fully claimed and illustrated in the accompanying drawings, in which:—

Figure 1 is a plan and sectional view of 45 a ratchet wrench, constructed in accordance with an embodiment of the invention, one of the pawls being shown in its inoperative position;

Figure 2 is a side elevation of the tool, 50 a portion of the bearing member being shown in section;

Figure 3 is a detailed view of the jaw or 55 socket member; and

Figure 4 is a perspective view of one of the pawls.

Referring to the drawings, 5 designates a handle member which is substantially stepped at its intermediate portion 6 to provide offset end portions 7 and 8, said end portion 7 having its extremity substantially coiled to provide a loop or a hand grip, while secured to the extremity of the end portion 8 is a bearing member 9.

The bearing member has an opening in one end for the reception of the end 8 of the handle, while its opposite end is closed, a socket or bearing 10 being provided in the last mentioned end portion of the bearing member, said socket extending through the side wall 11 of the bearing member, the opposite side wall 12 of the bearing member having a relatively small opening 13 which communicates with the bearing or socket 70 10. The side walls 14 and 15 of the bearing member are provided with registering slots 16 which communicate with the socket member 10, the opening in the first mentioned end of the bearing member communicating 75 with the socket member 10 so that the bearing member is substantially hollow.

A socket or jaw member 17 is provided, 80 said jaw member being made in various sizes according to the standard form of nut, 85 a number of said socket members of graduating sizes being provided for each handle so that the same may be enlarged. Each socket member includes an extension 18, the periphery of said extension having a series 90 of teeth 19 which extend longitudinally of the extension, the extension being also provided with a boss or lug 20 adapted to enter the opening 13 of the bearing member to properly position the socket member within 95 the bearing member. It will also be noted that a shoulder 21 is formed at the junction of the extension with the socket member, said shoulder being adapted to engage the edge of the socket member or portion of 100 the wall 11 of the bearing member so that lateral movement of the socket member is prevented.

To rotate the socket member within the bearing member, the extension 18 is provided with an annularly extending 105 endless channel or groove 22, said groove

extending laterally of the teeth 18 and inwardly of the outer face of said teeth, the groove being also disposed at the intermediate portion of the extension 18. In 5 the outer end wall of the bearing member, a relatively small threaded opening 23 is provided for the reception of a set screw 24, said screw being adapted to extend through the wall of the bearing member and 10 into the channel 22, to not only retain the socket member within the bearing member, but at the same time permit rotary movement of the handle member or socket member relative to each other.

15 To control the movement of the socket member, pawls 25 and 26 are provided, each pawl having its end portions 27 provided with a finger 28 and a tooth 29 adapted to engage the teeth of the extension 18. An 20 opening 30^a is provided in the opposite end portion 30 adjacent one side of said end portion, or in other words, off-center so that a cam extension 31 is thereby provided, the purpose of which will be hereinafter described. The 25 pawls 25 and 26 are intended to be disposed in the slots 16 of the bearing member so that the teeth 29 of the pawls will extend inwardly toward the extension 18 of the socket member, suitable pintles 32 being 30 passed through the side walls 11 and 12 of the bearing member and through the openings 30^a. By the use of the two pawls the tool can be operated in either direction, or can be locked.

35 To prevent the pawls from operating simultaneously, when it is desired to rotate the tool in one direction, there is provided novel controlling means comprising a plate 33 having a shaft 34 projecting from its intermediate portion. A spring 35 is intended to surround the shaft 34, one end of the spring engaging the plate, the opposite end of the spring engaging the extremity of the end portion 8 of the handle, the ends of the 40 plates projecting through the slots 16 of the bearing member.

In the operation of the device, the plate 33 is constantly urged into engagement with the ends 28 of the pawls through the medium 45 of the spring. In view of this, by the use of the cam extension 31 the desired pawl may be swung inwardly or outwardly according to the use of the tool. The pressure of the spring on the plate 33 causes said 50 plate to engage the pawl on either side of the cam extension to hold it in its operative or inoperative position so that the pawls may be alternately used. The pawl that is not in use substantially serves as a fulcrum 55 for the adjacent end of the plate 33, as shown in Figure 1, so that the opposite end of the plate may be urged by the spring into engagement with the pawl that is in use to prevent accidental disengagement of the 60 pawl from the teeth of the extension 65

18. With every handle member, a set of socket or jaw members are provided, said socket members being of various sizes. The desired socket member is inserted in the bearing or socket member 10, 70 the body portion of the socket, or that portion of the socket adapted to receive the nut, projecting beyond the bearing member so that the edges of the bearing member 10 engage the shoulder 20, while the projection 75 20 extends through the opening 13. The set screw 24 is then passed through the wall of the chamber 10 and into the groove 22 so as to permit rotary movement of the socket member, and prevent disengagement of the 80 same from the bearing member. The fingers 28 of the pawls permit the operator to readily adjust the pawls when desired.

From the foregoing it will be readily seen that this invention provides a novel form 85 of wrench capable of being rotated in a step by step fashion in either direction, or rotated as a unit, the stepped portion of the handle permitting a firm grip to be obtained without causing the hand of the operator to come 90 in contact with adjacent objects, so that the tool may be used with satisfaction for operating nuts disposed in obscure places.

What is claimed is:—

1. A wrench of the character described 95 comprising a socket member, a ratchet wrench member rotatable in the socket member, the socket member having a compartment adjacent the wrench member, pawls pivotally mounted in said compartment in 100 spaced relation to each other, each pawl having a cam extension adjacent its pivotal connection, a spring disposed in said compartment, a plate disposed between the spring and the pawls, said plate being arranged to hold one of the pawls in its inactive position, the cam extension of said inactive pawl providing a fulcrum for the plate, said fulcrum coacting with the spring to urge the plate into engagement with the 105 cam extension of the active pawl, and said active pawl into engagement with the teeth 110 of the wrench member.

2. Ratchet wrench pawl actuating means 115 embodying a socket member, a ratchet wrench member rotatable in the socket member, a pair of pawls pivoted in the socket member and adapted to engage the ratchet wrench member, the portion of the socket 120 between said pawls being unobstructed, each pawl having a cam extension adjacent its pivotal connection, a plate extending laterally of the space between the pawls, the ends of said plate being supported by the pawls, movement of the plate toward the wrench 125 being limited by the pawls, a spring mounted in the socket member and engaged with the plate, said plate being arranged to alternately hold either of the pawls in its active or inactive position, said inactive pawl pro- 130

viding a fulcrum for one end of the plate, the opposite end of the plate being urged unobstructedly by the spring toward and into engagement with the cam extension of 5 the opposite and active pawl.

3. Ratchet wrench pawl actuating means embodying a socket member, a ratchet wrench member rotatable in the socket member, a pair of pawls pivoted in the socket 10 member in spaced relation to each other, the portion of the socket between and above said pawls being unobstructed, each pawl having a cam extension adjacent its pivotal connection, one face of said extension being disposed substantially flush with the outer 15 side face of the pawl, a plate extending laterally of the space between said pawls, said plate being supported by the pawls, a

rod projecting from the central portion of the plate above the pawls, a spring disposed 20 centrally of the plate, and surrounding said rod, one end of said spring engaging the end of the socket, the ends of the plate being urged unobstructedly into simultaneous engagement with the ends of the pawls by the 25 spring and adapted to alternately hold either of said pawls in its inactive position, said side face and cam extension of the inactive pawl providing a fulcrum support for one end of the plate whereby the opposite 30 end of the plate may be moved unobstructedly by the spring into engagement with the end of the active pawl.

In testimony whereof I hereunto affix my signature.

RALPH E. MOYER.
